MULTIPLE-NEEDLE SEWING MACHINE

Gerhard Quitter, Bielefeld, Germany, assignor to Durkoppwerke Aktiengesellschaft, Bielefeld, Germany, a corporation of Germany

Application August 23, 1956, Serial No. 605,863

Claims priority, application Germany August 25, 1955

20 Claims. (Cl. 112—221)

The present invention relates to sewing machines having two or more needles which can be selectively taken into use and put out of commission by a coupling mechanism adapted to impart up-and-down reciprocating movement to only one needle at a time.

Machines of this character, which are used principally for making angularly extending seams, have heretofore been built only for relatively low speeds, such as about 1800 stitches per minute; the reason for this limitation has been the complexity of the coupling mechanism which had to be of sturdy and, hence, bulky construction in order to withstand the stresses and strains of frequent coupling and decoupling.

An object of this invention is to provide an improved coupling mechanism for the purpose set forth whose reciprocating components are of light weight so as to enable high-speed operation, e. g. at a rate of about 3000 stitches per minute, with a machine so equipped.

Another object of this invention is to provide dependable and easily operable means for positively coupling a needle bar or similar implement with a continuously moving driving member and for just as positively coupling such implement with a stationary retaining member after decoupling it from the drive member, thereby preventing frictional entrainment or accidental manual displacement of the inactivated implement.

A more specific object of this invention is to provide novel and improved means for selectively coupling a pair of nested tubular members for the positive entrainment of one by the other.

A feature of the present invention resides in the provision of a tubular needle bar received in an axially reciprocating sleeve and surrounding, in turn, an elongated, spring-loaded control member. Seated in a wall aperture of the needle bar is a coupling element adapted to be cammed in or out by the outer sleeve and by the inner control member, respectively. In its outwardly cammed position, into which it is urged by the spring-loaded control member, the coupling element positively engages the outer sleeve and causes the needle bar to be entrained by the latter; to decouple the needle bar from the sleeve, an abutment is placed in the path of a projecting extremity of the control member so as to cause relative displacement between this member and the needle bar, such displacement freeing the coupling element for inward camming by the sleeve and disengaging the latter from the needle bar. In order to prevent the needle bar from following the sleeve in its continuing reciprocation, there is preferably provided a second, similar coupling element co-operating with the control member so as to be cammed outwardly by the said relative displacement thereof, this second coupling element thereupon engaging another, stationary sleeve whereby the needle bar becomes immobilized. This condition obtains until the abutment is removed from the path of the control member so that the same can be restored by spring pressure to a position within the needle bar in which the second coupling element can be cammed inwardly by the stationary sleeve

2

and the first coupling element is cammed outwardly to re-engage the moving sleeve, whereupon entrainment of the needle bar by the last-mentioned sleeve is resumed.

In order to minimize the risk of jamming, there are preferably provided a plurality of coupling elements in angularly offset positions for both the moving sleeve and the stationary sleeve. A particularly simple form of coupling element is a steel ball of a radius approximately equal to the wall thickness of the needle bar.

10 The above and other objects, features and advantages of the invention will become more fully apparent from the following detailed description of a preferred embodiment, reference being had to the accompanying drawing in which:

15 Fig. 1 shows in sectional elevation a coupling mechanism according to the invention for the needles of a two-needle sewing machine;

Fig. 2 is a fragmentary elevational view of some of the elements shown in section in Fig. 1; and

Fig. 3 is a top plan view of the mechanism shown in Fig. 1.

At 1 there has been indicated in dot-dash outline the cast-iron frame of a sewing machine having an integrally molded head 2. Seated in this head are two tubular needle bars 3 and 4 guided for vertical reciprocating movement in a needle guide 5. A cross-head 6, whose crank pin 7 is connected with a suitable driving mechanism not shown, reciprocates in the manner indicated by the arrow whenever the driving mechanism is energized.

20 The needle guide 5 is swingable about an axle 9 which is lodged in the head 2 and secured to it by a setscrew 8. A collar 10, provided with a projection 10', is slidably mounted on axle 9 and is engaged by a stud 11 whose shank is fastened to a rod 12 by a setscrew 13. The

25 upper part of the needle guide provides enough clearance around collar 10 to enable the projection 10' thereof to be aligned with either of the two needle bars 3, 4 or to assume an intermediate position therebetween. In the drawing the projection 10' is aligned with needle bar 3.

30 The needle guide 5 is swingable about an axle 9 which is lodged in the head 2 and secured to it by a setscrew 8. A collar 10, provided with a projection 10', is slidably mounted on axle 9 and is engaged by a stud 11 whose shank is fastened to a rod 12 by a setscrew 13. The

35 upper part of the needle guide provides enough clearance around collar 10 to enable the projection 10' thereof to be aligned with either of the two needle bars 3, 4 or to assume an intermediate position therebetween. In the drawing the projection 10' is aligned with needle bar 3.

40 The needle guide 5 is swingable about an axle 9 which is lodged in the head 2 and secured to it by a setscrew 8. A collar 10, provided with a projection 10', is slidably mounted on axle 9 and is engaged by a stud 11 whose shank is fastened to a rod 12 by a setscrew 13. The

45 upper part of the needle guide provides enough clearance around collar 10 to enable the projection 10' thereof to be aligned with either of the two needle bars 3, 4 or to assume an intermediate position therebetween. In the drawing the projection 10' is aligned with needle bar 3.

50 The needle guide 5 is swingable about an axle 9 which is lodged in the head 2 and secured to it by a setscrew 8. A collar 10, provided with a projection 10', is slidably mounted on axle 9 and is engaged by a stud 11 whose shank is fastened to a rod 12 by a setscrew 13. The

55 upper part of the needle guide provides enough clearance around collar 10 to enable the projection 10' thereof to be aligned with either of the two needle bars 3, 4 or to assume an intermediate position therebetween. In the drawing the projection 10' is aligned with needle bar 3.

60 The needle guide 5 is swingable about an axle 9 which is lodged in the head 2 and secured to it by a setscrew 8. A collar 10, provided with a projection 10', is slidably mounted on axle 9 and is engaged by a stud 11 whose shank is fastened to a rod 12 by a setscrew 13. The

65 upper part of the needle guide provides enough clearance around collar 10 to enable the projection 10' thereof to be aligned with either of the two needle bars 3, 4 or to assume an intermediate position therebetween. In the drawing the projection 10' is aligned with needle bar 3.

70 The needle guide 5 is swingable about an axle 9 which is lodged in the head 2 and secured to it by a setscrew 8. A collar 10, provided with a projection 10', is slidably mounted on axle 9 and is engaged by a stud 11 whose shank is fastened to a rod 12 by a setscrew 13. The

75 upper part of the needle guide provides enough clearance around collar 10 to enable the projection 10' thereof to be aligned with either of the two needle bars 3, 4 or to assume an intermediate position therebetween. In the drawing the projection 10' is aligned with needle bar 3.

80 The needle guide 5 is swingable about an axle 9 which is lodged in the head 2 and secured to it by a setscrew 8. A collar 10, provided with a projection 10', is slidably mounted on axle 9 and is engaged by a stud 11 whose shank is fastened to a rod 12 by a setscrew 13. The

85 upper part of the needle guide provides enough clearance around collar 10 to enable the projection 10' thereof to be aligned with either of the two needle bars 3, 4 or to assume an intermediate position therebetween. In the drawing the projection 10' is aligned with needle bar 3.

wall thickness of the tubular needle bar so that this ball projects either outwardly from the bar or into the interior thereof. A second set of similar apertures 47, located farther down on bar 4, form a seat for three additional steel balls 44. An elongated control rod 39, axially traversing the bar 4 as well as a screw cap 40 at the upper end thereof, has its lower end guided in a bushing 42 serving as the lower anchor for a compression spring 43; this spring bears upon a shoulder 39' of rod 39 so as to urge the latter upwardly. A short piston rod 71 connects bushing 42 with a frusto-conical cam member 32 which is held at the level of balls 31 by a spacer rod 37; the lower end of this rod, shown eccentrically positioned so as not to interfere with the inward displacement of balls 44, is supported by a compression spring 36. A second frusto-conical cam member 46 is slidably held on rod 37 above the eccentric lower portion thereof, being urged downwardly by a compression spring 35 engaging the enlarged, screwed-on head of this rod. The length of spacer rod 37 is such that cam member 46, positioned for engagement with steel balls 44, will be out of contact with these balls while cam member 32 engages the steel balls 31, and vice versa.

The cross-head 6 forms a sleeve around each of the two needle bars 3 and 4. A conical recess 34 at the lower end of the sleeve surrounding bar 4 is adapted to cam inwardly the steel balls 31 in the absence of interference by conical member 32; in similar manner the sleeve surrounding bar 3 is provided with a conical recess 134 adapted to exert inward camming action upon the corresponding balls 131 thereof.

The lower portion of needle guide 5 is provided with two bushings 48 and 148 respectively surrounding the needle bars 4 and 3. The upper end of bushing 48 has a conical recess 48' adapted to exert inward camming action upon the steel balls 44 in the absence of interference by conical member 46; in similar manner the bushing 148 is provided with a conical recess 148' for the inward camming of the steel balls 144 in needle bar 3.

The displacement between the needle bars 3 and 4 relative to the cross-head 6 and to the needle guide 5 is limited by two collars 138 and 38 respectively carried by these bars. These collars are formed with external channels 138' and 38' respectively, as seen in Fig. 2, into which can penetrate pins 61 and 62 carried by cross-head 6 and pins 63 and 64 carried by needle guide 5. In this manner the needle bars 3 and 4 are secured against rotation. The needles 68 and 168 are mounted on holders 65 and 165 whose shanks are received in the lower extremities of needle bars 4 and 3, respectively, with a certain amount of axial play provided by a setscrew 66 whose head plays in a slot 67 of the needle bar as particularly illustrated for bar 3. The dimensioning of cross-head 6 and of guide 5 is such that the balls 31, 131 and 44, 144 will not be free, in any position of the needle bars, to drop out of their apertures.

Secured to the machine frame 1 by a screw 58 is a flat spring 57 whose lower end engages the shank of a knob 59 received in a slot 56 in the lower part of shift lever 14. This lever also carries a stud 60 adapted to block the lever in either of two limiting positions by its engagement with an edge of spring 57. To release the shift lever it is necessary to press the knob 59, whereupon the action of springs 49 and 50 in housing 19 (Fig. 3) centers the entire switching assembly 14, 17, 19 and 10 so as to place abutment 10' in its neutral position. A direct transition from one shifting position to the other is thereby prevented, thus insuring that the hitherto idle needle is fully actuated before the other needle is taken out of service.

The operation of the improved coupling mechanism described above will now be outlined in detail.

In the position shown in the drawing, needle 168 is elevated and inactive while needle 68 follows the move-

ments of cross-head 6. This is so because the balls 31 are cammed outwardly by cone 32 and bear upon the conical recess 34 of cross-head 6 which at the same time is engaged from above by the collar 38, needle bar 4 being thus in firm clamping engagement with the cross-head. As the needle bar reciprocates, it periodically reaches an upper dead-center position in which the projecting extremity of control rod 39 extends above the level of abutment 10' which at this time is in contact with the corresponding rod 139 of needle bar 3 and does not interfere with the operation of needle bar 4.

Let us now assume that the operator, desiring to immobilize needle 68 and to activate needle 168, has released lever 14 by pressing upon knob 59 and has swung this lever counter-clockwise (as viewed in Fig. 1) into its other limiting position. If this maneuver happened to occur at the instance when cross-head 6 was in its upper dead-center position, collar extension 10' was momentarily prevented by the rod 39 from occupying its right-hand position, rod 12 remained stationary and spring 20 was compressed by the counter-clockwise swing of housing 19 as viewed in Fig. 3. (Had the shift occurred from right to left, spring 21 would have been compressed.) Upon the next descent of rod 39 the spring 20 releases its stored energy and shifts abutment 10' into vertical alignment with rod 39. At the completion of the next ascent, rod 39 finds itself blocked while needle bar 4 continues to rise against the force of spring 35 which, yielding, allows the cone 32 to disengage from coupling balls 31. At the same time the cone 46 will be resiliently arrested, through the intermediary of compression spring 35, in a position in which it will cam the balls 44 outwardly and into contact with conical recess 48' at the instant when the bar 4 reaches the upper limit of its travel; the expansive force of spring 35 and the camming action of balls 44 imparts a slight additional upward push to needle bar 4 whereby the latter is driven beyond dead center and collar 38 is made to engage the upper portion of the needle guide 5, thus positively clamping the bar 4 to the stationary needle guide. The last-mentioned upward movement of the needle bar, occurring with the cross-head 6 virtually at standstill, results in the inward displacement of coupling balls 31 by the camming action of conical recess 34, these balls thus being retracted inside needle bar 4 so as no longer to interfere with the displacement of cross-head 6 relative to this bar. Any lowering of bar 4 through gravity or frictional entrainment is now impossible.

Meanwhile, the removal of abutment 10' from the top of rod 139 has allowed spring 136 within bar 3 to expand and to raise the cone 146 out of engagement with steel balls 144, at the same time lifting the cone 132 into contact with balls 131 through the intermediary of spring 135. As soon as the cross-head 6 again reaches its upper limiting position, it releases the balls 131 for outward movement and the residual expansion of spring 135 causes these balls, in camming engagement with conical recess 134, to drive the needle bar 3 slightly lower until collar 138 comes to rest upon cross-head 6 and completes the clamping action. The slight lowering of needle bar 3 also causes the conical seat 148' to cam inward the balls 144 so that relative motion between this needle bar and the guide 5 may now freely take place.

It will thus be seen that there has been provided an arrangement which, by the simple positioning of an abutment 10' in or out of the path of control member 39 or 139, the corresponding needle bar is firmly clamped to either a moving driving member 6 or a stationary guide or support 5. The coupling elements 31, 44 and associated parts are of small dimensions and do not necessitate an undue enlargement of the needle bars 3, 4 or of the cross-head 6. The spacing of the coupling elements and of the associated cam members 32, 46 has been so selected that the balls 44 will be able to move fully in-

wardly only after the balls 31 have positively locked the needle bar to the cross-head so that no uncontrolled descent of the needle bar can take place; also, the slight additional upward movement of the needle bar beyond dead center, resulting from the camming engagement between the balls 44 and the conical seat formation 48 as has been described, serves to raise the collar 38 above its normal upper limiting position so that it will not be periodically impinged upon by the reciprocating cross-head, whereby wear will be reduced. Apart from these advantages, however, it should be understood that some of the features of the invention may be embodied in systems using means other than those specifically illustrated for blocking the descent of the decoupled needle bar and/or for allowing the coupling elements 31 or 131 to recede into an inoperative position within the bar, and that in general the invention may be modified in various ways without departing from the spirit and the scope of the appended claims. Naturally, any number of needle bars may be selectively actuated, individually or simultaneously, by the mechanism herein disclosed or by its equivalents apparent to persons skilled in the art.

What is claimed is:

1. In a sewing machine, in combination, a reciprocable sewing implement, continuously movable actuating means and mechanism for selectively coupling said implement with said actuating means; said mechanism comprising an axially reciprocable tubular member operatively connected with said implement, an axially reciprocable sleeve member operatively connected with said actuating mechanism and surrounding said tubular member with freedom of relative axial motion, said tubular member having a wall with an aperture and radially displaceable coupling means in said aperture, cam means within said tubular member axially shiftable relatively thereto for moving said coupling means outwardly through said wall and into operative engagement with said sleeve member, thereby operatively coupling said tubular member with said sleeve member for entrainment thereby, resilient means internally anchored to said tubular member and axially bearing upon said cam means in a sense urging the latter into outward-camming action upon said coupling means, an axially displaceable control element operatively connected with said cam means and projecting from an end of said tubular member, abutment means adjacent said end of said tubular member selectively positionable in the path of said control element for axially displacing the latter along with said cam means relatively to said tubular member against the action of said resilient means upon movement of said tubular member in a predetermined axial direction, thereby releasing said tubular member from entrainment by said sleeve member, and blocking means adjacent said tubular member engageable therewith for arresting the return movement of said tubular member.

2. The combination according to claim 1, wherein said coupling means comprises a spherical element of a diameter greater than the wall thickness of said tubular member.

3. The combination according to claim 2, wherein said coupling means comprises a plurality of angularly spaced steel balls.

4. The combination according to claim 1, wherein said sleeve member has an extremity engageable with said coupling means and provided with a formation adapted to cam said coupling means inwardly in the arrested condition of said tubular member.

5. The combination according to claim 4, comprising stop means on said tubular member facing the other extremity of said sleeve member and positioned to be brought into contact with said other extremity by a camming engagement between said formation and said coupling means upon outward movement of the latter, whereby said sleeve member is positively locked to said tubular member.

6. The combination according to claim 1, comprising

5 a manually shiftable operating member for said abutment means and a resilient link between said operating member and said abutment means, said link enabling said abutment means to occupy a position in the path of said control element after the latter has withdrawn from a limiting position.

10 7. The combination according to claim 1, wherein said blocking means comprises a second, stationary sleeve member surrounding said tubular member, said tubular member being provided with a second aperture in its wall and with second coupling means in said second aperture engageable with said second sleeve member, further comprising second cam means within said tubular member axially shiftable relatively thereto for moving said second coupling means outwardly through said wall and into operative engagement with said second sleeve member, thereby fixedly anchoring said tubular member to said second sleeve member, and connecting means between said two cam means for rendering said second cam means effective 15 upon disengagement of the first-mentioned cam means from the first-mentioned coupling means.

20 8. The combination according to claim 7, wherein said second sleeve member has an extremity engageable with said second coupling means and provided with a formation 25 adapted to cam said second coupling means inwardly upon entrainment of said further member by the first-mentioned sleeve member.

25 9. The combination according to claim 8, comprising stop means on said tubular member facing the other extremity of said second sleeve member and positioned to be brought into contact with the last-mentioned extremity by a camming engagement between said formation and said second coupling means upon outward movement of the latter, whereby said second sleeve member is positively locked to said tubular member.

30 10. The combination according to claim 7, wherein said connecting means includes a resilient link.

35 11. In a sewing machine, in combination, a plurality of parallel needle bars, stationary guide means for said bars, said bars being axially reciprocable in said guide means, a drive member reciprocable relatively to said guide means in axial direction of said needle bars, first and second coupling means on each of said needle bars radially displaceable thereon for selective engagement respectively

40 with said drive member and with said guide means, a control element on each of said needle bars for respectively operating the first and the second coupling means thereof in a first and in a second relative axial position, said control element being axially shiftable relatively to

45 its needle bar for coupling the latter with either said drive member or said guide means by outwardly displacing said first and said second coupling means in said first and said second axial position, respectively, and abutment means on said guide means positionable in the path 50 of any of said control elements during entrainment of the respective needle bars by said drive member for decoupling an entrained needle bar from said drive member by relatively shifting its control element from said first into said second axial position.

55 60 12. The combination according to claim 11, further comprising resilient means anchored to each needle bar and bearing upon its control element for restoring the latter to said first axial position upon removal of said abutment means from its path.

65 13. The combination according to claim 12, wherein said needle bars are substantially vertical and provided with needle-holding means at their lower ends, said abutment means being positionable for engagement by said control elements upon said needle bars approaching an upper limiting position.

70 14. The combination according to claim 12, further comprising spring means on said guide means tending to maintain said abutment means in a neutral position out of line with said control elements, and shift means on

said guide means for displacing said abutment means against the action of said spring means.

15. The combination according to claim 14, further comprising delay means on said guide means engageable with said shift means for temporarily arresting the latter in an intermediate position, corresponding to the neutral position of said abutment means, upon operation of said shift means to displace said abutment means from alignment with one to alignment with another of said control elements.

16. The combination according to claim 15, wherein said delay means comprises detent means effective to lock said shift means in any of several operative positions and manually operable release means for inactivating said detent means and enabling said spring means to move said shift means into said intermediate position.

17. The combination according to claim 11, wherein said drive member and said guide means form axially spaced sleeves about said needle bars, said bars being provided with shoulders intermediate said sleeves for limiting the displacement of said needle bars relative to said guide means and to said drive member.

18. The combination according to claim 17, wherein said needle bars and said sleeves are cylindrical, said shoulders being formed by collars on said needle bars having eccentric channels, said drive member and said guide means being provided with projections adapted to enter said channels in a state of entrainment and at standstill of said needle bars, respectively, thereby maintaining said needle bars in predetermined angular positions.

19. A coupling mechanism for sewing-machine needles and the like, comprising an axially reciprocable first sleeve member, a stationary second sleeve member, a tubular member surrounded by both of said sleeve members with freedom of relative axial motion, said tubular member

having an apertured wall, first and second coupling means axially spaced in said wall and radially displaceable therethrough for selective engagement with said first and said second sleeve member, respectively, a control element for both of said coupling means extending within said tubular member and projecting from one end thereof with freedom of relative axial motion, said control element operatively engaging said first coupling means in a first relative axial position operatively engaging said second coupling means in a second relative axial position for radial movement thereof into coupling engagement respectively with said first and with said second sleeve member, abutment means adjacent said one end of said tubular member selectively positionable in the path of said control element during entrainment of said tubular member by said first sleeve member for shifting said control element relatively to said tubular member from said first into said second axial position, thereby decoupling said tubular member from said first sleeve member and coupling it with said second sleeve member, and drive means for reciprocating said first sleeve member.

20. A coupling mechanism according to claim 19, further comprising spring means anchored to said tubular member and bearing upon said control element for restoring the latter to said first axial position upon removal of said abutment means from the path of said control element, thereby decoupling said tubular member from said second sleeve member and coupling it with said first sleeve member for entrainment thereby.
